tion of Massachusetts

Original application November 2, 1945, Serial No.
626,316. Divided and this application Decem-
ber 31, 1949, Serial No. 136,382

7 Claims. (Cl. 129—16)

1

The subject matter of the invention is an improved and serviceable posting tray generally utilized to sustain a stack of record sheets in an orderly and clamped relation or in an appropriate unclamped relation to facilitate finger manipulation of the several sheets of the stack without however disturbing the proper order or classification thereof. Specifically the invention may be said to be directed to a simplified and expandible filing and posting tray for loose leaf sheets, index cards, ledger sheets, correspondence and other important documents to which reference may be quickly desired.

This application is a division of my prior application Serial No. 626,316 filed November 2, 1945, which issued as Patent No. 2,520,738 on August 29, 1950.

One object of the invention is the provision of a hollow base having spaced and slidably and laterally displaceable racks for increasing the effective width of the posting tray, the racks co-operating with novel toggle means to stabilize and insure uniform and smooth displacement of racks when bodily shifted into or out of the tray. The invention has a further object to provide means for normally holding the spaced racks locked to prevent accidental withdrawal or retraction thereof from or into the base of the tray. Other important objects, advantages and salient aspects of the invention will appear from the following detailed description considered in the light of the accompanying drawing wherein:

Fig. 1 is a top plan view of the tray shown partly broken away and partly expanded.

Fig. 2 is an enlarged front view of Fig. 1, shown partly broken away.

Fig. 3 is a longitudinal view of Fig. 1, shown partly in section and partly broken away to illustrate the internal construction.

Fig. 4 is a bottom plan view of Fig. 1.

Fig. 5 is an enlarged sectional view on the line 5—5 of Fig. 1.

Fig. 6 is an enlarged sectional view on the line 6—6 of Fig. 1.

Illustrative of the embodiment disclosed, the tray generally denoted T comprises a sheet metal base or support 10 having the medially arranged depending boss 11 defining a longitudinally disposed channel 12. To the spaced sides 13 of the hollow boss 11 (Figs. 1, 3 and 4) and adjacent the ends thereof, the U-shaped members 14 are appropriately fixedly secured within the channel 12. These U-shaped or channel-shaped members 14 characterize bearing means for rotatably sustain-

5 spaced screws 16 which have their inner cylindrical ends 17 rotatably guided and confined in the bearing block 18. The bearing block 18 has spaced upstanding sides 19 fastened to the spaced sides 13 of the boss 11 by the threaded members 20.

10 Parallel to and spaced above the aligned and rotatably guided screws 16 within channel 12 is the guide rod 21 which passes through openings 22 in the U-shaped and fixed end bearings 14 secured in the boss 11. This rod also extends through openings 23 in the spaced rectangular shaped blocks or runners 24 each having a threaded bore 25 in mesh with its respective screw 16 (Figs. 3 and 4). By the arrangement disclosed rod 21 is slidably sustained by the runners 24. This rod although slidably and removably supported by the U-shaped end bearings 14 is provided with threaded end portions 25' removably sustaining threaded members 26 which are 15 adapted to removably clamp against the front and rear walls 27 and 31 of the base, these walls embodying openings 28 (Fig. 3) for removably receiving the end threaded portions 25'. By this arrangement, guide rod 21 may be removed or disconnected from the base and withdrawn from the spaced runners 24 disposed within the boss 11. Conversely the rod 21 may be quickly threaded through the front and rear walls of the base and 20 through the blocks or runners 24 and held in a fixed relation to the base by the clamping members 26.

25 The base 10 which is preferably of sheet metal may be said to be characterized by spaced horizontal and flat sections 29 bent inwardly from sides 30 and 31 of the base. These plate sections 29 have their rear and front margins welded respectively to an inwardly extending flange 36 of the rear wall 31 and to a flange 38 extending inwardly of the front wall 27 on the base. Hence 30 these flat sections of plates are rigidly secured to the sheet metal base 10.

35 Superimposed on and substantially coextensive with the width and length of the horizontal and appropriately fixedly secured and spaced flat sections 29 of the base are the flat sheet metal panels 39. These panels 39 have roughened surfaces 40 to prevent slipping of the stack of sheets (not shown) vertically mounted between the spaced swingable follower or leaf 41 and the swingable compressor or leaf 42, each of which 40 is disposed transversely of the base.

45 Slidably longitudinally of the base, but disposed transversely thereof, and superimposed on 50 the spaced panels 39 are front and rear and

oppositely arranged substantially right angle shaped brackets or supports generally denoted 43, each of which comprises a horizontal leg 44 and a vertical leg 45. The horizontal legs 44 each bridge the channel 12 and each includes a circular bearing or opening 46 (Fig. 3) rotatably guided on and removably receiving the circular outer surface of an associate annular boss 47 projecting upwardly from the runners 24. Since the lower legs 44 of the brackets are rotatably retained on the bosses 47, these brackets may be said to be swiveled. As illustrated, each boss 47 includes an internally threaded bore which extends downwardly into its respective runner. The threaded shanks of screws 48 adjustably cooperate with the threaded bores of the runners while the enlarged heads of the screws cooperate with the legs 44 to preclude their accidental removal from the annular and hollow bosses 47.

If a screw 16 be rotated its runner 24 is slidably and longitudinally displaced along the guide rod 21, and consequently an associated leg 44 of the angle shaped bracket 43 is correspondingly linearly displaced relative to and longitudinally of the base 10.

Attached to the upstanding leg 45 of the brackets 43 and to the follower 41 and compressor 42 are the hingedly secured plates 50 and 51 having the fulcrum pins 52. By such hinged connection the follower and compressor may be selectively tilted relative to their brackets 43. For purposes of specification the pivoted follower 41 and compressor 42 may be considered as hinged plates for removably clamping a stack of sheet material placed in the tray, and these plates may be swung relative to the base 10 due to the hinged connecting means 50 and 51 carried by the brackets 43.

For controlling the degree of tilt of the follower or compressor an arcuate shaped handle 53 is associated therewith. The handle is fully described in my prior Patent No. 2,520,738, and the description will not be repeated in this application.

During use of the tray it is necessary at times to offset a selected sheet from the stack. Thus the width of the tray must be adjusted or compensated for to allow for such offsetting. The offsetting of a plurality of sheets from the stack causes the stack to have a greater thickness adjacent one edge of the leaves 41 and 42 than at the opposite edge. The swiveling of brackets 43 on bosses 47 permits rotational adjustment of the leaves 41 and 42 so that both edges of the leaves may be held tightly against adjacent surfaces of the stack of sheets. Also in actual practice it is necessary that posting trays be made fairly compact to occupy relatively small office space. According to the invention, provision has been made to permit offsetting of the record cards or sheets without however sacrificing compactness and simplicity in construction. To this end the racks generally denoted R are each adapted to be laterally projected relative to the sides 30 and 31 of the base 10.

Specifically each rack comprises spaced and horizontally disposed arms 90 and 91 each being slidably guided widthwise of the base in a gap or slot 92 (Figs. 5 and 6) formed by the inwardly turned flanges 36 and 38 of the rear and front walls 37 and 27 to which the top wall sections 29 are welded, and by flanges 93 of spaced angle plates 94 welded to the rear and front walls 37 and 27 of the base 10. Extending upwardly from each arm 90 and 91 is a vertical arm 95 (Fig. 3)

desirably coiled around and fastened to rails or rods 96. Thus each rack R embodies a rail 96 attached to spaced vertical arms 95 which in turn merge with the horizontally disposed arms 90 and 91 slidably guided widthwise of the base in gaps 92 and adapted to be slidably shifted into or out of the base through the spaced slots 97 at the ends of the sides 30 and 31. A horizontal arm 90 or 91 and its companion vertical arm 95 may be said to characterize a bent member or a bent arm.

Secured to each of the arms 90 and 91 of the spaced racks R is a link 98. More particularly, one end 99 of each link 98 is swiveled or hinged on a fulcrum pin 100 fastened to the arms 90 and 91. The arms 90 and 91 are superimposed on links 98 and in flatwise relation therewith.

The inside ends of links 98 each carry fulcrum means 101 on which the offset arms 102 of the bell crank levers 103 are hinged or swiveled. The bell crank levers 103 thus are free of the arms 90 and 91. However the elbows 104 of the bell crank levers are pivoted on the fulcrum posts or pins 105 anchored to the spaced sections 29 of the base.

The other arms 106 of the bell crank levers are hingedly connected on the fulcrum pins 107 fixedly carried at the end of the links 108 common to and interconnecting a companion pair of bell crank levers 103. By the arrangement disclosed, each bell crank adjacent the rear wall 37 of the base coacts with a helicoidal compression spring 109 having its ends secured to rectilinearly guided and spaced arms 91 and the arms 106 of said bell crank levers. The tendency of springs 109 is to hold the racks R in a normally retracted relation, that is, to hold the corresponding arms 90 (Fig. 4) of the spaced racks R yielding against the front wall 27 and to hold the other corresponding arms 91 of the racks away from the rear wall 37. By such action, each notch 110 on the toothed arms 90 may be automatically retained in interlocking relation with a fixed pin or detent 111 fixedly fastened to and extending downwardly from each section 29 of the hollow base 10. With a toothed arm 90 interlocked with its companion pin 111, its respective rack R is locked against bodily and lateral displacement relative to the base. A rack R may be unlocked, however, by applying a thrust on its hand rail 96 in a direction towards the rear end of the base, that is, towards the end wall 37. By such action the rack R so manipulated is bodily displaced longitudinally of the base and towards the rear of the latter and the teeth of the bar 90 formerly interlocking with a fixed pin 111 are rendered free. The spaced slots 97 in the spaced sides 30 and 31 of the base are adequate in length to permit bodily displacement of the racks R longitudinally of the base. The flanges 93 of the brackets 94 also guide longitudinal displacement of the racks R by preventing wobbling of the arms 90 and 91. Hence it is appreciated that each rack may be unlocked by displacing the latter longitudinally of the base. However, should manual pressure be removed from the rack which has been unlocked, its compression spring 109 bodily and automatically retracts the rack to its former locked relation with its cooperative locking pin 111.

Once a rack is unlocked it may be laterally projected to appreciably overhang the base, that is to say, if a toothed arm 90 is unlocked upon the manipulation of its companion rail 96, the 75 rack may now be bodily and slidably withdrawn

and set to a selected position in which the instant manual pressure is removed from the hand rail 96 the spring 109 recoils or retracts, automatically causing the toothed arm 90 to again interlock with its companion pin 111.

The linkages comprising each link 108 and the bell cranks 103 pivotally secured thereto permit uniform withdrawal or retraction of a rack R from and into the base and prevent binding of the arms 90 and 91 against the walls of the base. Moreover the action of these linkages also serve to guide the directional displacement of the arms 90 and 91 and cooperate with flanges 93 to preclude wobbling of the arms 90 and 91. The linkages in fact may be said to characterize equalizing means to facilitate smooth withdrawal or retraction of the racks R. Force applied to either rail 96 to move it outwardly is transmitted directly to the arms 90 and 91 on the same side of the tray as the rail to which the force is applied. If the force is applied closer to either arm 90 or 91 the particular arm closer to the point of application of the force would have a tendency to move outwardly faster and to a greater distance than the other arm. However, either arm moving outwardly must move the link 98 secured thereto by the pin 100. Such movement of link 98 moves bell crank 103 about its pivot 105 because the arm 102 is pivotally secured to link 98, as indicated at 101. The arm 106 of the bell crank is pivoted to link 108 and any movement imparted to either bell crank is transmitted through link 108 to the other bell crank on the same side of the tray. Since the pivots 105 are fixed, each bell crank must move the same amount, and the link 108 equalizes the force applied anywhere along the rail 96. The force is transmitted through the linkage equally to opposite ends of the tray and arms 90 and 91 are moved at the same rate so that they retain their parallel relationship and cannot bind against the base regardless of where the force is applied to the rail 96. Thus only finger tip pressure need be applied on the rail as 96 to first unlock its rack and subsequently bodily shift the same into or out of the base through the ends slots 97.

If it be assumed that a rack is unlocked, thereafter a slight lateral thrust on its rail will withdraw the rack. During such action the outer ends of the arms 102 of bell cranks 103 are directed outwardly by the arms 90 and 91 and the spring 109 is distended. Specifically, however, on withdrawal of a rack laterally, links 98 are first actuated, causing arms 102 of the bell crank levers 103 to simultaneously swing outwardly whereby the short arms 106 of these bell crank levers are actuated, causing the displacement of the interconnecting and common link 108 which serves to stabilize the action of the racks R to provide for their smooth operation, and overcome wobbling and binding as the racks R are severally operated. Having withdrawn a rack to its selected position, finger pressure is removed from its rail, and its compression spring recoils or retracts, causing the arms 90 and 91 to move to their normal positions wherein the toothed arm 90 is interlocked with the companion detent means 111. In the withdrawn relation of a rack, the width of the tray is increased. And of course both of the racks may be withdrawn to further increase such width. And where it is desired to move the racks to their normal position, each may be unlocked from its detent means 111, and bodily shifted inwardly into the base and again locked against bodily lateral displacement as is

well understood. However during retraction of a rack after having been unlocked, links 98 shift the long arms 102 of the bell crank levers inwardly, while the short arms 106 thereof coast to displace their interconnecting link 108, thus again equalizing the action of the linkage to preclude binding or wobbling of the arms 90 and 91 of the rack. The base 10 is provided with cushioning feet 120 to protect the surface upon which the tray is positioned.

Various changes may be made in details of construction and arrangement of parts without departing from the spirit of the invention or sacrificing any of the advantages thereof inherent therein.

I claim:

1. In a posting tray for holding a stack of sheets, a base for supporting said stack, a rack for increasing the effective width of said base comprising a rail disposed above said base and spaced arms sustaining said rail, said arms being shiftable relative to said base, stabilizing linkage interconnecting said arms and disposed within said base, said linkage having a plurality of fixed pivots to cause simultaneous displacement of said arms upon actuation of said rail to provide for uniform displacement of said arms out of or into said base upon bodily withdrawal or retraction of said rack relative to said base, and disengageable locking means to preclude bodily displacement of said rack relative to said base.

2. In a posting tray for holding a stack of sheets, a base having spaced openings, a rack for increasing the effective width of said base comprising a rail disposed above said base and spaced arms sustaining said rail, said arms extending through said openings and being shiftable in said openings longitudinally and laterally of said base, stabilizing linkage interconnecting said arms and disposed within said base to permit simultaneous displacement of said arms upon actuation of said rail to provide for uniform displacement of said portions out of or into said openings upon bodily withdrawal or retraction of said rack relative to said base, disengageable locking means to preclude bodily displacement of said rack relative to said base, said locking means comprising toothed means on one of said portions and detent means extending from said base, and spring means for normally urging said toothed means towards said detent means.

3. In a posting tray for holding a stack of sheets, a base having spaced openings, a rack for increasing the effective width of said base comprising a rail disposed above said base and spaced arms sustaining said rail, each of said arms extending through one of said openings, each of said openings being longer than the width of said arm extending therethrough, said arms being shiftable in said opening longitudinally and laterally of said base, stabilizing linkage interconnecting said arms and disposed within said base to permit simultaneous displacement of said arms upon actuation of said rail to provide for uniform displacement of said arms out of or into said openings upon bodily withdrawal or retraction of said rack relative to said base, detent means, one of said arms including spaced toothed means for disengageably interlocking with said detent means to prevent bodily displacement of said rack laterally of said base, said toothed means being disengageable from said detent means upon displacement of said rack

longitudinally of said base, and spring means for resisting said longitudinal displacement.

4. In a posting tray for holding a stack of sheets, a base having spaced openings, a rack for increasing the effective width of said base comprising a rail disposed above said base and spaced arms sustaining said rail, said openings being longer than the width of said arms, each of said arms extending through one of said openings and being shiftable in said opening longitudinally and laterally of said base, linkage pivoted to said base and arms and interconnecting the latter to allow simultaneous displacement of said arms upon actuation of said rail to provide for uniform displacement of said arms out of or into said openings upon bodily withdrawal or retraction of said rack relative to said base, and disengageable locking means to preclude bodily displacement of said rack relative to said base.

5. In a posting tray for holding a stack of sheets, a base for supporting said stack, a rack for increasing the effective width of said base comprising a rail disposed above said base and spaced arms sustaining said rail, said arms being shiftable longitudinally and laterally of said base; and stabilizing means equalizing the movement of said arms, said stabilizing means comprising links pivoted to said arms, bell crank levers pivoted to said links and said base, and another link common to said levers and pivotally connected thereto.

6. In a posting tray for holding a stack of sheets, a base having spaced openings, a rack for increasing the effective width of said base comprising a rail disposed above said base and spaced arms sustaining said rail one of said arms having a toothed edge, said arms being simultaneously shiftable relative to said openings longitudinally and laterally of said base; stabilizing means equalizing the movement of said arms, said stabilizing means comprising links pivoted to said arms, bell crank levers pivoted to said links and said base, another link common to said levers and pivotally connected thereto; detent means adjacent said toothed edge for interlocking there-

with to prevent displacement of said rack laterally of said base, and spring means interconnecting one of said levers and said other arm for bodily and longitudinally retracting said rack pursuant to its displacement longitudinally of said openings and away from said detent means to interlock said toothed portion with said detent means.

7. In a posting tray for holding a stack of sheets, a base having spaced sides including spaced openings, spaced racks for increasing the effective width of said base, each of said racks comprising a rail disposed above said base and spaced arms sustaining said rail, one of said arms having a toothed edge, said arms being simultaneously shiftable longitudinally and laterally of said base in the spaced openings of one of said sides, stabilizing means for each of said racks, each of said stabilizing means equalizing the movement of the arms of its rack, each of said stabilizing means comprising links pivoted to said arms, bell crank levers pivoted to said links and said base, and another link common to said levers and pivotally connected thereto; detent means adjacent to said toothed edge for interlocking therewith to prevent displacement of said rack laterally of said base, spring means interconnecting one of said levers and said other arms for bodily and longitudinally retracting said rack automatically for interlocking with said detent means, each of said racks pursuant to unlocking of its toothed arm from its companion detent means being bodily displaceable laterally of said base under the control of said stabilizing means.

35
